UNITED STATES PATENT OFFICE.

WILLIAM L. MUENDER, OF MONTFORD, WISCONSIN.

CONCENTRATING-TABLE.

1,015,823.

Specification of Letters Patent.

Patented Jan. 30, 1912.

Application filed January 7, 1911. Serial No. 601,418.

To all whom it may concern:

Be it known that I, WILLIAM L. MUENDER, a citizen of the United States, residing at Montford, in the county of Grant and State of Wisconsin, have invented a new and useful Concentrating-Table, of which the following is a specification.

It is the object of this invention to provide a dry concentrating mechanism, where-
10 by the ore will be separated into different masses of different specific gravities, at successive steps in the operation, the gangue being maintained apart from the ore, by an air blast, until the ore has been completely separated, into masses of different specific gravities.

Another object of the invention is to provide a novel form of riddle, so constructed that, when the same is operated in
20 conjunction with an air blast, and a reciprocating casing, the gangue and the ore will be maintained separate and apart, to be deposited individually in different localities.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

35 In the accompanying drawings—Figure 1 is a view of the invention in side elevation; Fig. 2 is a vertical longitudinal section; Fig. 3 is a top plan; Fig. 4 is a
40 transverse section on the line A—B of Fig. 3; Fig. 5 is a perspective, showing a portion of the lower face of one of the riddles; Fig. 6 is a fragmental top plan of the casing; and Fig. 7 is a fragmental transverse section, the view showing the manner in which the gate co-operates with other portions of the structure.

45 Referring particularly to the drawings, and noting Fig. 1, that end of the device to which the numeral A is applied, will be considered as the forward end of the machine, that portion of the structure to which the letter B is applied, being considered as the rear end of the machine.

In carrying out the invention, there is provided as a primary and fundamental element, a box-like casing 1, closed at the bottom, and equipped with suitable bearings 2, to which the upper extremities of rock arms 3 are pivoted, the rock arms being pivotally mounted at their lower ends in pillow blocks 4, resting upon a suitable support 5.

To the forward end of the casing 1, a pitman 6 is operatively connected, the pitman carrying at its forward end, a strap 7, embracing an eccentric 8, adjustably held upon a shaft 9, mounted for rotation in bearings 10, supported by a suitable foundation 11, the shaft 9 being equipped with a pulley 12, which may be taken as typical of any suitable means whereby rotation may be imparted to the shaft 9.

Through the bottom 14 of the casing 1, an air blast pipe 15 extends, a deflector 16 being positioned above the discharge end of the pipe 15, within the casing 1.

As denoted by the numeral 17, and as seen most clearly in Fig. 1, the upper edge of the casing 1 slants downwardly from the forward end of the casing toward the rear end of the casing, so that when the ore is deposited upon riddles, supported upon the upper edge of the casing 1, the ore will move gravitationally from the forward end of the casing toward the rear end thereof when a reciprocating motion is imparted to the casing 1, through the rotation of the shaft 9, the eccentric 8 and the pitman 6 obviously imparting a reciprocation to the casing, when the shaft 9 is rotated, as will be clearly understood, the casing 1, of course, tilting upon the rock arms 3.

At spaced points, the side walls of the casing are united by cross bars 18, longitudinal bars 19, disposed midway between the side walls of the casing, serving to unite one cross bar 18 with the next cross bar, the longitudinal bars 19 uniting the terminal cross bars 18 with the end walls of the casing 1. Located between the longitudinal bars 19 and the side walls of the casing 1, are gratings 20 the longitudinal bars 19 being depressed below the upper edges of the side walls of the casing 1, and the gratings 20 sloping downwardly toward the longitudinal center of the casing, as an examination of Fig. 4 will render clear.

A mesh work fabric 21 is extended over the top of the casing 1, the fabric covering 21 being depressed along the longitudinal center of the casing 1, by means of securing strips 22, superposed upon the covering, and united with the longitudinal bars 19.

The invention further includes a plurality of riddles, disposed longitudinally of the casing 1, in downwardly inclined relation, each riddle discharging into the next adjoining one, from the forward end of the casing toward the rear end thereof. Each riddle comprises a head board 23, a tail board 24, and side walls 25, the tail board 24 of one riddle being disposed in close proximity to the head board 23 of the next adjoining riddle. In the intermediate portion of each tail board 24 there is, as Fig. 5 will render evidence, a depending lug 26, adapted to register in, but not to close entirely, an opening 27 (see Fig. 6) in the fabric covering 21, the opening 27 being located adjacent the longitudinal center of the casing 1 and in the line of greatest depression of the covering 21. The several riddles are held upon the casing 1 by means of bolts 29, or other securing elements, extending through mating ears 28 upon the side walls 25 of the riddles, and upon the side walls of the casing 1. The riddles are equipped with division plates 30, adapted to rest upon the securing strips 22, the division plates 30, in their lower edges, being depressed below the lower edges of the side walls 25 of the riddles. From the division plates 30, ore riddles 31 extend laterally toward the side walls 25 of the riddles, and upon the ore riddles 31, gangue skimmers 32 are superposed, the skimmers 32 crossing the riddles 31. The riddles 31 and the skimmers 32 both slant downwardly from the side walls 25 of the riddles, toward the division plates 30, and in the lower edges of the riddles 31, adjacent the division plates 30, there are notches 33, having functions which will be described hereinafter. The gangue skimmers 32 discharge over the tail boards 24 of the riddles, the riddles 31 discharging against the side faces of the tail boards, as an examination of Fig. 8 will render evident, the skimmers 32 converging toward the forward end of the casing 1, while the riddles 31 converge toward the rear end of the casing.

Supported upon each tail board 24, is a bracket 34, in which is mounted a vertically moving gate 35, adapted to effect a closure of the opening 27, these openings 27 communicating with laterally extended chutes 36, prolonged, as seen in Fig. 1, through one of the side walls of the casing 1.

At the forward end of the casing 1 any suitable delivery mechanism, indicated conventionally at 37, may be positioned, while to the rear end of the casing 1, the gangue spout 38 is secured.

The operation of the device is as follows: The ore is delivered into the forward end of the structure, through the conventionally shown mechanism 37, the ore being deposited upon the uppermost riddle. Reciprocation being imparted to the casing 1, through the instrumentality of the pitman 6, in the manner hereinbefore described, the heavier material will work downwardly between the riddles 31 and the skimmers 32, to rest upon the fabric covering 21. By reason of the fact that the riddles slope downwardly toward the longitudinal center of the machine, the heavier material following the riddles 31, will move toward the division plates 30, the notches 33 in the lower edges of the riddles, permitting the heavier material to move longitudinally of the casing 1, and to come into abutment, ultimately, with the tail board 24 of the uppermost riddle. By opening the gate 35, in the uppermost riddle, the heavier material may be permitted to flow away through the first discharge tube 36. During the foregoing operation, a blast of air will have been supplied to the interior of the casing 1, below the covering 21, through the instrumentality of the air blast pipe 15. This air blast, delivered beneath the covering 21, will serve to elevate the gangue above the heavier ore, the gangue following the skimmers 32, to be discharged, along with the lighter ore, over the tail board 24 of the first riddle, and over the head board 23 of the next riddle, into the last named riddle.

The operation above described in connection with the first, uppermost riddle, will take place upon the intermediate riddle, and upon the last riddle, successive masses of ore being drawn away through the discharge spouts 38, the gangue, at last, passing over the tail board 24 of the last, lowermost riddle, and entering the gangue spout 38.

From the foregoing it will be seen that the heaviest material will be segregated by the first discharge chute 36, a mass of material of slightly less specific gravity being delivered by the next chute 36, a third mass of material, of still less specific gravity being delivered by the last chute 36, the gangue ultimately passing out of the rear end of the casing, into the spout 38. The reciprocation of the casing 1 will serve to separate the ore, according to its specific gravity, the air blast, delivered through the pipe 15, serving to carry the gangue upwardly, so that the skimmers 32 may pass the gangue from one riddle to another, and finally deposit the gangue in the gangue spout 38, the gangue being held apart from the ore, during the time that the ore is being segregated and withdrawn through the chutes 38, by the reciprocation of the casing 1.

It will of course be understood, without

specific delineation, that the casing 1 may be of any length, and that any number of riddles may be employed thereon.

Having thus described the invention, what is claimed is:

- 5 1. In a device of the class described, a casing; a mesh work covering thereon; a riddle upon the casing above the covering, the riddle comprising intersecting ore riffles and gangue skimmers, the skimmers being superposed upon the riffles, the riffles and the skimmers slanting downwardly toward the longitudinal center of the casing, there being openings in the lower edges of the 10 riffles, adjacent the longitudinal center of the casing, to permit the ore to move longitudinally of the casing; means for imparting a longitudinal reciprocation to the casing; and means for supplying fluid under 15 pressure beneath the mesh work covering.
- 20 2. In a device of the class described, a casing; a mesh-work covering thereon; a riddle carried by the casing, above the covering, the riddle comprising a tail-board and intersecting ore riffles and gangue skimmers, the riffles discharging against the tail- 25

board, and the skimmers being extended across the tail-board, the riffles and the skimmers slanting downwardly toward the longitudinal center of the table; there being 30 openings in the lower edges of the riffles, adjacent the longitudinal center only of the casing; a movable gate carried by the casing adjacent the discharge end of the tail-board and adapted to receive the material 35 from the riffles, the gate being extended but part way across the casing, and being located adjacent the longitudinal center of the casing; the covering being provided with an opening for which the gate constitutes a closure; means for imparting a longitudinal reciprocation to the casing; and means for supplying an air blast beneath the covering.

In testimony that I claim the foregoing as 45 my own, I have hereto affixed my signature in the presence of two witnesses.

WILLIAM L. MUENDER.
